Specification for Design.

Patented Aug. 6, 1918.

Application filed August 11, 1915. Serial No. 45,067. Term of patent 14 years.

To all whom it may concern:

Be it known that I, EMIL C. TECKTONIUS, a citizen of the United States, residing at Racine, in the county of Racine and State of Wisconsin, have invented a new, original, and ornamental Design for Band-Fasteners, for which the following is a specification, reference being had to the accompanying drawing, forming a part thereof.

Figure 1 of the drawing is a side elevation, Fig. 2 a top plan view, Fig. 3 an end elevation as viewed from the left relative

to Figs. 1 and 2, and Fig. 4 an end elevation as viewed from the right relative to Figs. 1 and 2, of a band fastener for tanks, silos, kilns and the like, showing my new design.

I claim:

The ornamental design for a band fastener, substantially as shown.

EMIL C. TECKTONIUS.
